[57] **CLAIM**

I claim the ornamental design for a hinge, as shown and described.

DESCRIPTION

FIG. 1 shows a perspective view of the hinge.
FIG. 2 shows a side elevation view from the left side of FIG. 1.
FIG. 3 shows a side elevation view from the right side of FIG. 1.
FIG. 4 shows an elevation view looking from the back of FIG. 1.
FIG. 5 shows a view looking from the bottom of FIG. 1; and,
FIG. 6 shows a view looking from the top of FIG. 1 of the hinge in its open position.
